WILLIAM E. ROBERTS, OF RIVERDALE, OREGON.

GAS-ENGINE.

1,313,836.

Specification of Letters Patent. Patented Aug. 19, 1919.

Application filed March 30, 1917. Serial No. 158,583.

To all whom it may concern:

Be it known that I, WILLIAM E. ROBERTS, a citizen of the United States, residing in Riverdale, county of Multnomah, and State 5 of Oregon, have invented certain new and useful Improvements in Gas-Engines, of which the following is a specification.

My invention relates to gas, or internal combustion, engines, and more particularly 10 to an improved rotary valve for controlling the supply of explosive mixture to the cylinders, and the exhaust of the burnt gases therefrom.

One of the salient objects of my invention 15 is to provide a rotary valve of tapered form, with means for yieldingly holding said tapered valve seated in a tapered valve casing, but in such manner as will not interfere with the rotation of said valve member 20 therein for the purpose of controlling the inlet and exhaust of the explosive mixture to and from the cylinders.

In order to explain my invention I have 25 illustrated one practical embodiment thereof in the accompanying sheet of drawings, which I will now describe.

Figure 1 is a vertical sectional view taken 30 longitudinally of a gas engine embodying my invention, being a section taken on line 1-1 of Fig. 2;

Fig. 2 is a vertical cross sectional view, taken on line 2-2 of Fig. 1;

Fig. 3 is a sectional view through the 35 valve casing showing the valve advanced a quarter turn from the position thereof shown in Fig. 1;

Fig. 4 is a similar sectional view showing the valve advanced a further quarter turn;

Fig. 5 is a similar view showing the valve 40 advanced a still further quarter turn;

Fig. 6 is an enlarged sectional view taken on line 6-6 of Fig. 1;

Fig. 7 is a developed view, being a circumferential view of the co-operating hub-like portions on the adjacent ends of two 45 valve members, showing the rollers intended to cause the rotary movement of the valve members by engagement with the over-lapping hub-like portions of said valve members; and

Fig. 8 is an enlarged perspective view of one of the valve sections.

Referring now to the drawings more in detail, my invention as here shown 55 comprises four cylinders 1, 2, 3 and 4, within

which are mounted, respectively, four pistons 5, 6, 7 and 8, each connected with a crank shaft 9, having bearings at 10-10, and provided at one end with a wheel or pulley 11, and at its other end with a beveled gear 12, which meshes with a beveled gear 13, on a vertical shaft 14, provided at its upper end with a beveled gear 15, which meshes with a beveled gear 16, on a shaft 17, which extends through a valve casing 18, 60 provided with a water jacket 19, said valve casing being closed at its opposite ends by means of end caps, as 20 and 21, which form bearing boxes for the opposite ends of the valve shaft 17.

Mounted within the valve casing 18, are four bearings or lining sleeves 22, 23, 24 and 25, of straight cylindrical form on their outer diameters, and of tapering cylindrical form on their inner diameters, said bearing 70 sleeves being placed within the valve casing in pairs with their larger inner diameters adjacent each other. For example, the bearing sleeves 22 and 23, form a chamber whose larger diameter is at their meeting edges 80 and which chamber tapers toward its opposite ends. This is also true of bearing sleeves 24 and 25. At the joint between bearing sleeves 23 and 24, the smaller inner diameters thereof are in register with each 85 other. Mounted within said bearing sleeves in the valve chamber and on the valve rod 17, are four tapered valve members, 26, 27, 28 and 29, each of said valve members being provided inwardly from its opposite ends 90 with longitudinally and circumferentially extending cavities, or pockets, as 26^a and 26^b, 27^a (27^a not seen in Fig. 1), 28^a and 28^b, 29^a and 29^b, the pockets, or cavities, differentiated with the letter "a" opening in one 95 direction, and those differentiated by the letter "b" opening in the opposite direction. Said cavities or pockets also have longitudinally extending outlets radially through the sides of the valve members, adapted to 100 register with the communicating openings into the cylinders 1, 2, 3 and 4, said valve openings, where shown, being designated 27^c and 29^c. Mounted on the shaft 17, in the ends of valve members are expansion rings 105 17^a, to prevent leakage through the valve members around the shaft 17.

The adjacent ends of said tapered valve members are provided with hub-like clutch extension portions as 30 and 31, of irregular 110

form, the portion 30 being clearly shown in Fig. 8, the hub-like extensions on the two adjacent valve members being adapted to overlap each other with a coiled spring 32, 5 surrounding both of said overlapping hub-like portions. The shaft 17 is provided between the pairs of valve members with through pins 17^a, upon the opposite ends of which, at the opposite sides of the shaft 17, 10 are mounted two rollers 33. The relationships of these parts may be understood from Fig. 7. Attention is called to the fact that the rollers 33—33 would engage the hub-like extensions 30 and 31, on the valve members 15 for the purpose of rotating said valve members when said shaft 17 is rotated. In the preferred form of the invention said rollers engage inclined cam portions, as 30^a—31^a, thus not only tending to give a rotary motion 20 to said valve members, when said shaft 17 is driven, but also to cause a slight longitudinal movement thereof out of their seats, by reason of the cam action between the rollers and the cam surfaces of the hub-like 25 extensions engaged thereby. The springs 32, interposed between adjacent valve members, tend to normally move said valve members apart, and to cause them to seat in the tapered bearing sleeves, or linings, within 30 the valve casing.

Said valve casing is provided with two intake openings, as 34 and 35, which may be connected with the usual intake manifolds, the intakes being preferably between 35 the valve members between which are placed the expansion springs 32, whereby said expansion springs are not over-heated as they would be were the exhaust through these openings. The exhaust openings are designated 36, 37 and 38, and may also be connected with a suitable exhaust manifold, not shown.

Thus it will be seen that as the valve members are simultaneously rotated by the 45 shaft 17, their intake and exhaust pockets, or cavities, are alternately moved into register with the inlets to the respective cylinders 1, 2, 3 and 4. In Fig. 1 the inlet is closed and compression is about to take 50 place in cylinder 1. In cylinder 2, the intake is about to take place, the valve 27 being in a position whereby its pocket 27^b is in register with the inlet to said cylinder and also is in communication with the intake openings 34. In cylinder 3, the entrance to the cylinder is closed and the firing or explosion is about 55 to take place, while in cylinder 4, the exhaust is about to take place, the valve 29 being so positioned that its pocket, or cavity, 29^b, opens said cylinder to the exhaust outlets 38.

Thus by the turning of the four valve members each cylinder is successively 60 opened to a supply of explosive mixture, 65

then closed for compression and firing, and then opened into communication with the exhaust outlet. Said valve members are turned by the engagement of the rollers 33—33, with the hub-like clutch portions 70 on the adjacent ends of each pair of valve members, which engagement not only turns the valve members with the shaft, but also tends to move said valve members, by a cam action, slightly longitudinally out of their 75 tapered valve seats and against the tension of the springs 32, to facilitate their turning.

Attention is called to the fact that by having a tapered valve member seated in the tapered seat, with means for yieldingly 80 holding it to the valve seat, means is thus provided for maintaining a film of oil between the valve member surface and its valve seat. The tendency of the valve member, when revolved, in the valve seat will 85 be to move slightly longitudinally away from its seat. While it is believed that this action will take place, because of the tapered form of the valve member, I have also provided a cam action between the 90 driving shaft for the valve members and the valve members, which will operate to produce a slight movement of the valve members away from their seats and against the tension of the springs between the valve 95 members. This general construction, it will readily be seen, will take care of any expansion and contraction which may be due to variation of the temperature of either the valve member or the valve casing, and 100 also takes care of any slight variation in the relative sizes of the valve members and their valve seats.

While I have shown the preferred embodiment of my invention, I am aware that 105 changes can be made in the details as here shown and described, without departing from the spirit thereof, and I do not, therefore, limit the invention to the details shown, except as I may be limited by the hereto 110 appended claims.

I claim:

1. In a gas engine, in combination, a plurality of cylinders, a valve casing common to all of said cylinders and having communicating passageways thereto, a plurality of tapered valve members rotatably seated in said valve casing and each provided with pockets adapted to be moved alternately into register with a communicating passageway to one of said cylinders, means between said valve members, for rotating the same, and means therebetween for normally and yieldingly holding said tapered valves in their valve seats within said valve casing, 115 substantially as described.

2. In a gas engine, a valve casing having tapered valve seats and passageways therefrom, a plurality of tapered valves rotatably seated end to end in said valve seats, 120

130

- and each provided with oppositely opening pockets adapted to be moved alternately into register with one of the passageways from said valve casing, a driving shaft extending through said valve casing and through said valve members with driving means therefor operating therebetween, and driving connections between said driving shaft and said tapered valve members for rotating the same, said driving connections being interposed between the adjacent ends of each pair of tapered valve members, the pairs of said tapered valve members being spaced apart, substantially as described. 10
3. In a gas engine, a valve casing having tapered valve seats and passageways therefrom, a plurality of tapered valve members rotatably seated in said valve seats and each provided with oppositely opening pockets 15 adapted to be moved alternately into register with one of the passageways from said valve casing, a driving shaft extending through said valve casing and through said valve members with driving means therefor, driving connections between said driving shaft and said tapered valve members for rotating the same, said driving connections being interposed between the adjacent ends 20 of each pair of tapered valve members, the
- pairs of said tapered valve members being spaced apart, and a spring interposed between the pairs of tapered valve members and operating to normally move them apart and into their respective valve seats. 30
4. In an engine, a valve casing having tapered valve seats therein, two tapered valve members rotatably seated in said valve seats at a space apart, means for driving them together in the same direction, and means interposed therebetween normally moving said valve members apart and into their respective valve seats. 35
5. In an engine, a valve casing having tapered valve seats therein, two tapered valve members rotatably seated in said valve seats at a space apart, driving means interposed between said valve members for driving them together in the same direction, and means therebetween normally moving said valve members apart and into their respective valve seats. 40

Signed at Portland, Multnomah county, Oregon, this 23rd day of March, 1917.

WILLIAM E. ROBERTS.
